(57) **CLAIM**

The ornamental design for a ligation clip with controlled tissue compression, as shown and described.

DESCRIPTION

FIG. 1 is a side perspective view from a distal end of a ligation clip with controlled tissue compression of the present design with the ligation clip in an open position; FIG. 2 is a perspective view from a proximal end of the ligation clip shown in FIG. 1 in the open position; FIG. 3 is a side view of the ligation clip shown in FIG. 1 in an open position; FIG. 4 is a side view of the ligation clip shown in FIG. 3 with the ligation clip in a clamped position; FIG. 5 is a side perspective view from the distal end of an alternate version of the ligation clip shown in FIG. 1 in accordance with other aspects of the present design with the ligation clip in the open position; FIG. 6 is a side perspective view from the proximal end of the ligation clip shown in FIG. 5 with the ligation clip in the open position; FIG. 7 is a side view of the ligation clip shown in FIG. 6 with the ligation clip in the open position; FIG. 8 is a side perspective view of the ligation clip shown in FIG. 7 with a hinge portion of the ligation clip in an open position and the ligation clip in an open position; FIG. 9 is a side view of the ligation clip shown in FIG. 7 in the clamped position; FIG. 10 is a side perspective view from the distal end of another alternate version of the ligation clip shown in FIG. 1 in accordance with other aspects of the present design with the ligation clip in the open position; FIG. 11 is a side perspective view from the proximal end of the ligation clip shown in FIG. 10 with the ligation clip in the open position; FIG. 12 is a side perspective view of the ligation clip shown in FIG. 11 with a hinge portion of the ligation clip in an open position and the ligation clip in the open position; FIG. 13 is a side view of the ligation clip shown in FIG. 12 in the clamped position; and, FIG. 14 is a side view of the ligation clip shown in FIG. 7 in the clamped position.

The broken lines shown in the figures are included for the purpose of illustrating portions of the ligation clip and form no part of the claimed design.
